UNITED STATES PATENT OFFICE.

WALTER H. SCHUSSLER, OF PHILADELPHIA, PENNSYLVANIA.

TOBACCO-FEEDING MECHANISM.

Application filed May 8, 1928. Serial No. 107,630.

The object of this invention is to devise novel means for feeding short filler or shredded tobacco which is commonly known in the trade as scrap tobacco.

5 A further object of my invention is to devise a novel method of feeding tobacco involving the steps of removing the tobacco from proximity to a discharge outlet and permitting it to return in a loosely associated condition into proximity to the discharge outlet, and preferably thereafter the loosely associated tobacco is removed through said discharge outlet.

15 With the above and other objects in view as will hereinafter more clearly appear, my invention comprehends novel tobacco feeding mechanism which can form an integral part of a cigar bunching machine or an attachment thereto.

20 It further comprehends novel tobacco feeding mechanism wherein novel means are provided for causing the particles of tobacco to be loosely associated, and, for this purpose, I have disclosed a preferred embodiment in which the tobacco is contained in a revolving drum having provision for preventing the packing together of the particles of tobacco. Novel means are provided for removing the loose tobacco from 25 the drum, and novel means are also provided for conveying the fed tobacco to a desired place of utilization, such as, for example, a cigar bunching machine.

30 It further comprehends a novel method of feeding tobacco.

Other novel features of construction and advantage will hereinafter more clearly appear in the detailed description and the appended claims.

40 For the purpose of illustrating the invention, I have shown in the accompanying drawing a typical embodiment of it, which, in practice, will give reliable and satisfactory results. It is, however, to be understood that this embodiment is typical only

45 and that the various instrumentalities of which my invention consists can be variously arranged and organized, and the invention is not, therefore, limited to the precise arrangement and organization of these instrumentalities.

Figure 1 is a side elevation of a tobacco feeding mechanism embodying my invention.

55 Figure 2 is a top plan view.
Figure 3 is a section on line 3—3 of Figure 1.

Figure 4 is a section on line 4—4 of Figure 3.

60 Similar numerals of reference indicate corresponding parts.

Referring to the drawings:—

For the purpose of illustration, I have shown the tobacco feeding mechanism as having a supporting frame work 1 which 65 may be integral with or separate from a tobacco treating or bunching machine or which may form an attachment to a machine of such character.

70 The frame has connected with it a supporting conveyor which at its upper end is in the form of a chute or hopper 3 into which the tobacco is placed in any desired or conventional manner.

75 The support 2 is recessed as at 4 in order to form a bearing for a revoluble tobacco receiving and feeding drum 5 which is provided with shaft 7 having a pulley 8 which is adapted to receive a drying belt 9, which is driven by any desired source of power.

80 The end plate 6 has connected with it the bars 10 which are also connected with the revoluble drum 5 for example by spot welding. The drum 5 is provided with a guard 12 having the outwardly extending ears 13 into which pass fastening devices 14 in the form of bolts and nuts, the bolts passing through the ends of the arms of the spider 15 and being secured in position by means of the nuts.

85 The spider 15 is stationary and is carried by or forms a part of the frame work 1. The bars 10 are radially disposed within the drum 5 and are of greater width in proximity to the guard 12, and each bar is 90 provided with a number of slots 16. The guard or drum cover 12 at its lower end is provided with a discharge opening 17, which has connected with it in any desired manner the downwardly curved bars 18 which form 95 a grate or grid.

100 The bars form slots between them which

register with the slots 16 and into these slots are adapted to extend the tobacco removing fingers 19 which are carried by the spaced wheels 20 secured to the shaft 21.

5 The wheels 20 are secured in proper spaced relationship by means of the spaced members 22, and a fastening member 23 secured to the wheels on the shaft 21. The driving shaft 7 has fixed to it a gear 24 10 which meshes with a gear 25 on the shaft 21 to drive the latter.

The shaft 21 has fixed to it a pulley 26 around which passes a belt 27, which latter also passes around a pulley 28 on a shaft 15 29, journaled in the machine frame and carrying a roller 30, around which passes an endless conveyor 31 in the form of a belt or apron, which also passes around a roller 32 carried by a shaft 33 journaled in 20 the frame work 1.

The drum 5 on the shaft 7 which effects its rotation, has its axis of rotation inclined to the horizontal as seen in Figure 4, so that the tendency of the tobacco in the drum 5 25 is to move inwardly towards the discharge opening 17.

The operation of my novel tobacco feeding mechanism will now be apparent to those skilled in this art, and is as follows:—

30 The driving belt 9 is driven by any desired source of power to effect the revolution of the driving shaft 7 and thereby of the drum 5. The shafts 7 and 21 are inter-gearred so that they revolve in unison. The 35 tobacco is placed in the hopper and passes into the drum 5. Due to the provision of the bars 10, the tobacco is lifted as the drum revolves and drops to the bottom in a loosely associated condition and does not become 40 dense and compact.

The feeding fingers 19 of the wheels 20 remove the loose tobacco from the drum and discharge it onto the conveyor belt 31 which conveys the tobacco to a desired place 45 of utilization for further treatment, such as for example, a tobacco bunching machine.

The fingers 19 extend into the slots 16 so as to remove the tobacco, which latter falls down the grid formed by the bars 18 50 onto the conveyor 31.

Any surplus tobacco that is left in proximity to the discharge opening of the hopper is carried up by the bars 10, and, as the drum revolves, these bars discharge the 55 tobacco without agitation of a character which would tend to crumble or break the particles of tobacco.

It will be apparent from the foregoing that in accordance with my present method, 60 tobacco in proximity to a discharge outlet is removed and permitted to return in proximity to such outlet in a loosely associated condition. The loosely associated tobacco can then be removed through the discharge

outlet in any desired manner and fed to a 65 desired point of utilization or further treatment.

If the tobacco is dense and compact it is impossible to feed it in definite quantities so that the bunches will contain a uniform 70 weight of tobacco and be of uniform size.

Furthermore, the cigars draw better when the tobacco is in a loose condition. The rolling operation has a tendency to compact the tobacco so that if the tobacco is too 75 compact when fed, the tobacco in the finished cigar has too great a density.

If tobacco is fed in the usual manner, it packs together as it piles up, and this objection is overcome in my present method 80 and apparatus.

I furthermore obtain a better mixture of the fine and coarse particles of tobacco, without necessitating the employment of agitators and baffles which have a tendency 85 to break the tobacco.

I furthermore obtain a better and more homogeneous mixture of the blends.

The drum 5 may be foraminous or in the 90 form of a screen.

In so far as I am aware, I am the first in the art to remove a mass of tobacco at a discharge outlet from such outlet and then permit it to drop in a loose condition, and I desire my claims to such features to receive the broad and generic interpretation to which a pioneer in the art is entitled.

While I have shown a preferred form for carrying out my novel method in practice, it will be understood that many different constructions can be employed.

It will now be apparent that I have devised a new and useful tobacco feeding mechanism and method of feeding tobacco which embodies the features of advantage enumerated as desirable in the statement of the invention and the above description, and while I have, in the present instance, shown and described a preferred embodiment thereof which will give in practice satisfactory and reliable results, it is to be understood that this embodiment is susceptible of modification in various particulars without departing from the spirit or scope of the invention or sacrificing any of its advantages.

Having thus described my invention what I claim as new and desire to secure by Letters Patent, is:—

1. Tobacco feeding mechanism comprising a revoluble drum having its axis of rotation inclined to the horizontal and having a discharge opening at its lower end, and means to remove tobacco from said opening.

2. Tobacco feeding mechanism comprising a tobacco receiving drum having its axis of rotation inclined to the horizontal and having its outer periphery cut away at its

lower portion, a guard covering said cut away opening to form a discharge opening for the tobacco, and means to remove the tobacco from said discharge opening.

5 3. Tobacco feeding mechanism comprising a tobacco receiving drum having its axis of rotation inclined to the horizontal and

having its outer periphery cut away at its lower portion, a guard covering said cut away opening for the tobacco, a grid leading from said discharge opening, and means passing into said grid to remove the tobacco from said drum. ¹⁰

WALTER H. SCHUSSLER.
